J. N. Bryant
Attorney

UNITED STATES PATENT OFFICE.

GEORGE F. CRASS, OF ITHACA, NEW YORK.

LOCK.

Application filed July 5, 1922. Serial No. 572,882.

To all whom it may concern:

Be it known that I, GEORGE F. CRASS, a citizen of the United States of America, residing at Ithaca, in the county of Tompkins and State of New York, have invented certain new and useful Improvements in Locks, of which the following is a specification.

This invention relates to certain new and useful improvements in locks, and has particular reference to a lock embodying a plurality of tumbler pins that are adapted to be shifted to certain positions to permit operation or opening of the lock.

The primary object of the invention resides in the provision of a lock wherein a casing supporting a rotatable barrel, has a plurality of tensioned plunger pins that are adapted to be projected into the openings formed in said barrel to hold the barrel and locked bolt carried thereby against movement, separate tumbler pins slidably mounted in the openings in said barrel adapted to be operated for shifting the tumbler pins carried by the casing to permit rotation of the barrel and causing the tumbler pins carried by the casing to ride upon the periphery of said barrel.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views.

Figure 1 is a side elevational view of a lock constructed in accordance with the present invention,

Figure 2 is an end elevational view of the same showing the rotatable barrel of the lock and the key opening in the end of the barrel,

Figure 3 is a plan view of the opposite end of the lock, showing by dotted lines, the locking bolt associated with the rotatable barrel,

Figure 4 is a top plan view of the lock,

Figure 5 is a cross sectional view taken

on line V—V of Fig. 1 showing the rotatable barrel within the lock casing and the tensioned tumbler pin carried by the lock casing extending into openings and in engagement with tumbler pins carried by the rotatable barrel.

Figure 6 is a longitudinal sectional view taken on line VI—VI of Fig. 4 showing the positions assumed by the tumbler pins when the barrel and bolt carried thereby are in locked position, and further showing the initial entrance of the operating key into the rotating barrel,

Figure 7 is a longitudinal sectional view similar to Fig. 6, showing the operating key entirely received within the rotating barrel with the key partially rotated to cause the tumbler pin carried by the barrel to elevate the tumbler pin carried by the lock casing to permit rotation of the barrel within the casing,

Figure 8 is a top plan view of the rotatable barrel removed from the casing,

Figure 9 is a cross sectional view taken on line IX—IX of Fig. 8 showing the key engaging lugs carried by the rotatable barrel, and

Figure 10 shows cross sectional views of various type of keys that may be employed for operating the lock.

Referring more in detail to the accompanying drawing, the lock embodies a casing formed of end walls 1 and 2 connected by a cylindrical casing 3 and longitudinal brace bars 4 positioned above the casing 3 as clearly shown in Figs. 1, 4 and 5, the extreme upper ends of the walls 1 and 2 being connected by a rib 6.

A barrel 7 is rotatably disposed within the cylindrical casing 3, one end thereof being shouldered as at 7^a for engagement with a corresponding shoulder formed on the adjacent end wall 2, as shown in Figs. 6 and 7 while the opposite end of the barrel extends beyond the casing 3 and receives a collar 8 retained thereon by a set screw 9 to present axial movement of the barrel within the casing. As shown by dotted lines, a locking bolt 10 is eccentrically pivoted to the projecting end of the barrel and

2
is shifted to its locked and unlocked positions by rotation of the barrel.

A plurality of tumbler pins is associated with the rib 6 of the lock casing and the 5 rotatable barrel 7, said rib being provided with a plurality of spaced alined openings 11 within which tumbler pins 12 are slidably mounted, said pins being tensioned by the spring 13 that engage the outer ends 10 of the pins and are retained in the outer ends of the openings 11 by the strip bar 14 countersunk within the upper edge of the rib 6 and retained so positioned by the fastening devices 15. The barrel 7 is similarly 15 provided with spaced alined openings 11^a that are adapted to register with the openings 11 in the casing rib while said openings 11^a freely support sliding tumbler pins 12^a. It will be noted that the tumbler pins 20 12 are of equal lengths, as shown in Fig. 7 while the tumbler pins 12^a carried by the rotatable barrel 7 are of unequal lengths for purposes presently to appear.

To support the tumbler pins 12 and 12^a 25 when the barrel 7 is in a locked position relative to the cylindrical casing 3, an axially disposed rod 16 positioned in the eccentric bore 17 of the barrel 7, projects from the end wall 18 of said bore and 30 terminates at a point inwardly of the key hole opening 19 in the shouldered end of the barrel 7, the tumbler pins 12^a being supported by the rod 16 as shown in Fig. 6 while the spring pressed tumbler pins 12 35 are supported on the outer ends of the tumbler pins 12^a. In this position, the spring pressed tumbler pins 12 extend from the openings 11 in the casing rib 6 into the openings 11^a in the barrel 7 forming an 40 interlocking connection between the barrel 7 and cylindrical casing section 3 to prevent rotary movement of the barrel within the casing.

The key employed for shifting the tumbler pins 12 and 12^a, and rotating the barrel 7 45 for shifting the lock bolt 10 embodies a shank having a plain side 20 and an oppositely disposed longitudinally extending rib 21 that is notched as at 22 while said key shank is provided with an axial bore 23 to 50 be received on the rod 16 of the rotatable barrel 7. The outer end of the shank carries a suitable head 24, and the rib 21 of the key shank adjacent said head is provided 55 with a notch 25 that is adapted, upon rotation of the key in the barrel 7 to receive the shoulder 26 depending from the key hole opening 19 to prevent removal of the key from the lock.

In positioning the key within the bore 17 60 of the rotatable barrel 7, the axial bore 23 of the key shank receives the rod 16 and the tumbler pins 12^a ride over the plain upper side 20 of the key shank as shown in Fig. 6, the forward beveled edge of the inner end

of the key shifting the tumbler pins 12^a to permit insertion of the key within the locking barrel. When the key has been entirely received within the barrel and upon the rod 16, the same is rotated by the head 24 to 70 present the several notches 22 in the rib 21 for reduction of the tumbler pins 12^a, it being understood that the notches 22 are of different depth to compensate for the different lengths of the tumbler pins 12^a for shifting the same to the position shown in Fig. 7, at which time the contacting edges of the tumbler pins 12 and 12^a are alined with the connecting walls between the periphery of the rotatable barrel 7 and the inner face of 80 the cylindrical casing section 3 as illustrated. With the key rotated to the position shown in Fig. 7, the end 21^a of the rib 21 is presented for engagement with the lug 27 carried by the inner wall of the bore 17 at 85 the inner end thereof as shown in Figs. 6, 7 and 9, further rotation of the key causing the rib end 21^a thereof to engage said lug 27 for rotating the barrel 7 to shift the lock bolt 10. During this movement, the adjacent ends of the tumbler pins 12 and 12^a 90 will ride over the contacting surfaces between the rotatable barrel 7 and the inner face of the cylindrical casing section 3. In order to effect a reverse rotation of the lock barrel 7, the key is rotated upon the rod 16 which will permit the tumbler pins 12^a to fall upon the plain side 20 of the key shank and upon continued rotation of said key, the end 21^a of the key shank rib will engage 95 the lug 27^a within the inner end of the bore 17 of the barrel 7 for shifting the barrel and lock bolt 10, and also presenting the openings 11^a in the barrel for registration with the openings 11 in the casing rib 6 for the springs 13 to force the tumbler pins 12 into the barrel openings 11^a as shown in Fig. 6.

With the tumblers 12 and 12^a so positioned, the latter rest upon the upper plain surface of the key shank, and said key is then removed from the lock casing or barrel with the bolt 10 retained in its locked position. In Fig. 10 of the drawing there are illustrated several types of key that may be employed with a lock of this character, in each instance, the shank 20^a of each key having a plain side, and an axial bore with a longitudinally extending notched rib 28 of various transverse configurations carried thereby. 115

From the above detail description of the device, it is believed that the construction and operation thereof will at once be apparent, and while there are herein shown and described the preferred embodiments of the present invention, it is nevertheless to be understood that minor changes may be made therein without departing from the spirit and scope of the invention as claimed. 120

What is claimed as new is:—
In a lock of the type described, a casing, 130

a barrel rotatable in the casing, a lock bolt carried by the barrel, radially disposed tumbler pins carried by the casing and barrel with the barrel carried pins being of varying lengths, said barrel having a bore therein, a key for operating the tumbler pins, cooperating guide means for the key carried by the key and barrel with the barrel carried means positioned axially of the bore thereof, and cooperating means carried by the inner 10 end of the barrel bore and the key to affect rotation of the barrel in opposite directions.

In testimony whereof I affix my signature.

GEORGE F. CRASS.
